NEEDLE THREADER

Walter Frey, Quedlinburg, Germany

Application October 4, 1933, Serial No. 692,075
In Germany October 10, 1932

5 Claims. (Cl. 223—99)

This invention relates to a needle threader of the hook type, in which the needles are automatically straightened and threaded without straining the eyes or requiring a steady hand.

5 Threaders of this class are known already, in which straightening and threading take place automatically, the straightening operation being effected by moving the needle during its introduction into the device between movable jaws in

10 the direction of its longitudinal axis.

Compared with existing devices, the invention provides that the needle during its introduction into the threader passes first between straightening surfaces having different coefficients of friction and then along notched slide bars for stopping the needle at the desired point, the slide bars being preferably staggered to straighten the needle in its longitudinal axis by the wedge effect of the notches and to prevent clamping of 20 the thread when the threaded needle is removed. One of the straightening surfaces is preferably movable and acted upon by a spring which imparts to it the application pressure required for straightening the eye, and one of the slide bars 25 is preferably provided with supplementary cushioning. The needle can be passed through the straightening surfaces and moved up to threading position by means of the fingers, unless a special appliance is used for these operations. The bar 30 limiting the descent of the needle rises to a certain degree to facilitate accurate fixing of the height of the eye. A hooked needle serving for drawing the thread through the eye is preferably movable to permit automatic adjustment to 35 different eye levels. Suitably disposed safety pins or surfaces prevent operation of the device carrying the hooked needle before the needle is in threading position.

40 The new threading device is furthermore so arranged that when the needle is in threading position the eye of the needle stands perfectly clear to facilitate threading.

45 By way of example, two embodiments of the invention are illustrated in the accompanying drawing, in which Figures 1 to 3 show a threader in which the needle is passed through by hand while Figs. 4 to 7 show a threader in which the needle is brought into position by a lever. Figs. 8 to 11 illustrate the threading process for needles of different sizes.

50 In the drawing, Figure 1 is a front view of the first embodiment; Fig. 2, a sectional side view thereof on the line II—II, of Fig. 1; Fig. 3 shows the rear wall with the support removed; Fig. 1a is a side view of a groove; Fig. 4, a front view of

the second embodiment; Fig. 5, a sectional side view thereof on the line V—V, of Fig. 4; Fig. 6, a sectional top view thereof on the line VI—VI, of Fig. 5; Fig. 7, a sectional top view thereof on the line VII—VII, of Fig. 5; Fig. 8, an enlarged section similar to Fig. 2 with respect to a large needle which is straightened while the thread drawing hook is in highest and receiving position, as indicated by dotted lines, and the threaded needle with thread guide is shown in broken lines when 10 leaving the device; Fig. 9 is a top view of Fig. 8 with the needle disposed between the slide bars shortly before reaching threading position; Fig. 10 is a view similar to Fig. 2 with respect to a small needle which is straightened while the 15 dotted drawing hook is in lowermost and thread receiving position; Fig. 11 is a top view of Fig. 10 with the needle arranged within the notches of the slide bars in threading position.

55 Referring to the drawing and to the modification shown in Figs. 1, 2, 3, 8, 9, and 10, a housing of suitable construction is provided having a needle receiving channel member R disposed on an angle to the length of the housing. The needle b is initially positioned in this channel R, being 20 inserted until it strikes a limiting rail g, which in Fig. 1 is indicated as being a curved member.

25 A fixed needle straightening member i is carried by the housing above the rail g, and upper and lower friction members d and e are yieldably 30 carried by the housing, which coact with the straightening member i in turning the needle b as it is moved in a vertical swinging movement out of the channel R. These needle straightening members d and e are preferably of different 35 degrees of friction so that the desired turning movement will be accomplished. The needle straightening members i, d, and e have a needle receiving notch k, and when the needle reaches this notch k the eye thereof will be in alignment 40 with a threading hook o which is pivotally carried as at s by an operating lever P, and tensioned by means of a spring q.

45 A thread supporting means v is secured to the housing in a position confronting the hook o so that the bill u of the hook o will engage the looped portion of the thread. The rail g has a flange f on the side opposite from the friction member e so that the inner end of the needle will be clamped firmly. A fixed member B is carried 50 by the housing above the rail g against which the needle is adapted to bear during the raising of the outer end of the needle. This needle positioning member B prevents the needle from moving past the threading position, which position is in a posi- 55

tion confronting the bill *u* of the hook *o* and directly in line with the bill *u* and the thread support *v*.

The device functions as follows:

5 In the position A, the needle *b* is pushed by hand along the groove *R* up to the bar *g*, regardless of the direction of its eye, as indicated in Figs. 1, 1a, and 3.

When turned about the pivot *B* (Fig. 3) in the 10 direction of the arrow *a* the needle *b* will pass between the straightening faces *F*, *f* having different coefficients of friction, as shown in Figs. 2, 8, and 9, the difference in coefficients of friction producing during the passage of the needle *b* 15 a rotary motion thereof about its longitudinal axis.

The straightening surface *F* is secured to a movable support *G*, as shown in Figs. 1 and 9, which under the action of the spring *c* causes 20 friction between the faces *F*, *f* and the needle *b* as required for rotation the latter. The rotary motion of the needle *b* continues until the flat sides of the needle eye are adjacent to the surfaces *F*, *f*, whereupon further rotation is no longer possible. 25 Until threading position has been attained the needle *b* will carry out only a sliding motion between the faces *F*, *f* and the surface *f* and the slide bars *d*, *e* connected with the support *G* prior to entering the notches *k* of the guide bar *i* and 30 slide bar *d* where it will be firmly held between the members *f* and *k*. If the needle *b* has accidentally attained the correct position while being inserted in the thresher and the surfaces of the eye are thus already parallel to the straightening motion *a* and to the faces *F*, *f*, the needle 35 will not be rotated while moving in the direction of the arrow but slide instantly to its threading position between the faces *F*, *f* and the slide bars *d*, *e*.

40 Owing to the drawing action of the spring *c*, the slide bar *e* presses the lower part of the eye of the needle *b* firmly against the surface *f* to prevent further displacement or rotation of the needle *b* while, simultaneously, the distance *m* 45 will prevent clamping of the thread during removal of the needle *b* from the thresher, as indicated in Fig. 8.

In order to bring the needle *b* inserted at A up to the slide bar *g* safely on threading level, the 50 bar *g* rises in the direction of passage of the needle to the extent indicated by *n* in Fig. 3, the needle being securely pressed against the bar *g* by the friction between the faces *F*, *f*, the slide bars *d*, *e*, and the guide bar *i*, which counteracts the rising 55 motion of the needle.

When the needle *b* has reached threading position, the lever *p* carrying the hooked needle *o* is moved in the direction of the arrow, whereupon the needle *o* held in lowermost position by the 60 spring *q* and the stop *r* meets with its point the lowest edge of the eye opening and, while under tension by the spring *q*, passes through the eye, the hooked needle *o* adjusting itself automatically to the different diameters *Sg* or *Sk* of the eye of the needle *b*.

When the lever *p* is stopped by the member *t*, the hooked needle *o* has been passed through the eye to such an extent that the thread can be placed in front of the receiving hook *u*. 70 The thread is drawn over a double-sided guide *v* to insure uniform seating. The receiving hook *u* enters the hollow space formed by the sides of the guide *v* and is thus protected against damage.

During return of the lever *p* the needle *o* draws 75 the thread through the eye by means of the hook

u, whereupon the needle is upwardly removed from the thresher while the ends of the thread continue to be drawn through the eye until the shorter end is out. Then the uniform pull of the two ends relative to the hook *u* will stop, the thread become disengaged from the hook *u* and the needle *b* be threaded and ready for use. 5

The lever *p* carries a safety surface *z*, as shown in Figs. 1 and 2, and can be operated, together with the hooked needle *o*, only after the needle *b* has passed this surface *z* and reached threading position, so that the needle *o* cannot be damaged.

In the construction shown in Figs. 4 to 7, *T* is an inlet funnel and *h*, a lever carrying the funnel *T*, by means of which the needles *b* contained in the member *T* are passed between the straightening surfaces *F* and *f*, as indicated in Figs. 4, 5, 6. *w* designates a safety pin on the lever *p*; *x*, a safety pin on the lever *h*; *y*, a recess on the lever *h* for the member *w*, as shown in Figs. 4, 5, 6, 7. The members *w* and *x* lock one another, so that the lever *p* carrying the hooked needle *o* can be actuated only when the lever *h* is advanced to such an extent that the member *x* of the lever *p* 25 can pass through the recess *y* of the lever *h*. Premature operation of the lever *p* and, as a result, damage to the hooked needle *o* are therefore excluded. All other parts correspond to the parts shown in Figs. 1 to 3, if they bear the same 30 reference letters, and the further operation of the device is like that of the first-described construction. To repeat briefly:

Manual threading by means of this first construction shown in Figs. 1 to 3 is carried out by 35 passing the needle *b* by hand through the groove *R* up to the bar *g*, as indicated in Figs. 1, 3, 4, 5, whereupon the needle is turned into threading position, as shown in Figs. 1 and 4. Then the lever *p* is advanced, the thread placed over the 40 guide *v* and the lever *p* pushed back. Threading is now completed, and the threaded needle *b* is drawn out of the device.

When threading with the device shown in Figs. 4 to 7 the operator passes the needle *b* through the funnel *T* on the lever *h* at A up to the slide bar *g*, whereupon the lever *h* is turned in the direction *a* until threading position is attained, as indicated in Fig. 4, and the lever *p* advanced. Then the thread is placed over the guide *v* and 50 the lever *p* returned. Since threading is now completed, the threaded needle can be taken out.

I claim:—

1. A needle thresher comprising opposed cam members one movable relative to the other, said members being disposed in different planes for engagement with the periphery of a needle at points spaced longitudinally of the needle, a member disposed below said cam members to limit the insertion of the needle, a stop means 55 for limiting the swinging movement of the needle, and a pivoted thread pulling hook supported for movement relative to a needle engaging said stop means.

2. A needle thresher comprising opposed cam members one movable relative to the other, each of said cam members adapted to exert a pressure against the needle different from that of the opposite cam member and said cam members being disposed in different planes for engagement 70 with the periphery of a needle at points spaced longitudinally of the needle, a member disposed below said cam members to limit the insertion of the needle, a stop means for limiting the movement of the needle, and a pivoted thread pulling 75

hook supported for movement relative to a needle engaging said stop means.

5. A needle threader comprising opposed cam members one movable relative to the other, said cam members being disposed in different planes for engagement with the periphery of a needle at points spaced longitudinally of the needle, a member disposed below said cam members to limit the insertion of the needle between said cam members, and a thread pulling hook supported for movement transverse to the length of the needle.

10. A needle threader comprising opposed members movable one relative to the other and adapted to frictionally contact with the periphery of a needle whereby to turn said needle upon movement of the needle longitudinally of the members, one of said members having a needle engaging surface different from the needle engag-

ing surface of the other member, means for stopping the movement of the needle, and a thread pulling hook supported for movement transverse to the length of the needle.

5. A needle threader comprising opposed members movable one relative to the other and adapted to frictionally contact with the periphery of a needle whereby to turn said needle upon movement of the needle longitudinally of the members, said members being disposed in different planes and one of said members having a needle engaging surface different from the needle engaging surface of the other member, means for stopping the movement of the needle relative to the members, and a thread pulling hook supported for movement transverse to the length of the needle.

15. WALTER FREY.
